UNITED STATES PATENT OFFICE.

NELSON NOËL, OF NEW BEDFORD, MASSACHUSETTS.

DESIGN FOR A PENNANT.

54,762.

Specification for Design.

Patented Mar. 23, 1920.

Application filed June 25, 1919. Serial No. 306,746. Term of patent 3½ years.

To all whom it may concern:

Be it known that I, NELSON NOËL, a citizen of the United States, residing at New Bedford, in the county of Bristol and State of Massachusetts, have invented a new, original, and ornamental Design for a Pennant, of which the following is a specification, reference being had to the accompanying drawing, forming part thereof.

The figure is a plan view of a pennant showing my new design.

I claim:

The ornamental design for a pennant, as shown.

NELSON NOËL.

Witnesses:

ASA AUGER,
DELIA J. GIRARD.
